UNITED STATES PATENT OFFICE

141,368

DESIGN FOR A BROOCH PIN OR SIMILAR ARTICLE

William W. Hobé, New York, N. Y.

Application March 8, 1945, Serial No. 118,358

Term of patent 7 years

(Cl. D45—19)

To all whom it may concern:

Be it known that I, William W. Hobé, a citizen of the United States of America, residing in New York city, county of New York, and State of New York, have invented a new, original, and ornamental Design for a Brooch Pin or Similar Article, of which the following is a specification, reference being had to the accompanying drawing, forming part thereof, wherein,

I claim:

The ornamental design for a brooch pin or similar article, substantially as shown.

WILLIAM W. HOBÉ.
